UNITED STATES PATENT OFFICE.

WILLIAM J. CURTIS, OF WILMINGTON, DELAWARE, ASSIGNOR TO NATIONAL ADJUSTABLE BED AND SPRING COMPANY, OF WILMINGTON, DELAWARE.

ADJUSTABLE BED AND LOCKING MEANS THEREFOR.

1,277,198.

Specification of Letters Patent. Patented Aug. 27, 1918.

Application filed October 22, 1917. Serial No. 197,900.

To all whom it may concern:

Be it known that I, WILLIAM J. CURTIS, a citizen of the United States, residing at Wilmington, in the county of New Castle 5 and State of Delaware, have invented certain new and useful Improvements in Adjustable Beds and Locking Means Therefor, of which the following is a specification.

The present invention relates to improvements in that type of bedstead embodying adjustable sections especially designed for the comfort of invalids, and more particularly to locking mechanism for such sections whereby they may be adjusted and held in 15 different positions.

The object and advantages of the invention will be apparent by reference to the following description and claim, when read in connection with the annexed drawings, 20 wherein:

Figure 1 is a fragmentary view of a bedstead frame having my present invention applied thereto and shown in elevation;

Fig. 2 is a sectional view looking at one 25 of the locking arrangements from the side opposite that shown in Fig. 1;

Fig. 3 is a vertical sectional view on the line 3—3 of Fig. 2;

Fig. 4 is a horizontal sectional view on the 30 line 4—4 of Fig. 2;

Fig. 5 is a perspective view of the locking bolt keeper or retainer;

Fig. 6 is a perspective view of the special 35 form of operating lever for the locking bolt; and

Fig. 7 is a perspective view of the locking bolt and spring.

The type of bedstead to which this invention is particularly adapted is disclosed 40 clearly in my previous Patent No. 1,059,842, granted April 22, 1913, and embodies the main frame 1, the sub-frame 2 supported by the hangers 3 and an adjustable section 4 pivotally connected at either end on the 45 brace rod 5. The frame construction of the bedstead is preferably of angle iron which affords the required rigidity for devices of this character. The end or adjustable sections 4 are of the customary U-shaped form, 50 the extremities of the side members, however, being provided with arms 4' extending downwardly in contiguous relation to an apertured segment or plate 6 which is suitably attached to the sides of the frame 1 by 55 fastening members 7. A special feature of

formation of the arms 4' is the provision of an upturned flange 8 which engages about the edge of the arcuate segment plate 6 and tends to hold the parts in proper relation against displacement from strains incident 60 to the application of stress to the plates through the locking means now to be described.

Attached to each of the downwardly extending arms 4' of the adjustable bed section or sections is a keeper or retainer 9 most clearly shown in Fig. 5 of the drawings, this element being U-shaped in formation and having an aperture 10 through which the shank of the locking bolt or locking-member 11 projects. The arm 4' is provided with an aperture through which the head of the bolt 11 projects for engagement with the series of openings 12 in the segment plate 6. A spring 13 surrounds the shank of the locking bolt and is held in place by the retainer 9, normally holding the bolt in locking engagement. As will be noted in Figs. 4 and 5, the retainer is formed with a laterally projecting extension 14 upon which is pivotally 70 mounted a special form of bell crank lever 15. This retainer, locking bolt and crank lever form an assembly unit adapted for attachment as a unit to the adjustable section, thereby facilitating the manufacture of 75 the bed. This last mentioned member is provided with a vertically disposed arm 15' having a bifurcation 16 engaging about the shank of the bolt 11 between the head of said bolt and the pin 17. Any suitable 80 manipulative connection is provided for actuating this lever 15 to cause the bolt to be retracted or disengaged from the segment plate 6 and I preferably employ such type of means as is disclosed in my previous patent 85 hereinbefore referred to and consisting of a pivoted lever connected to the end of the adjustable section as indicated at 18, one end of which cooperates with a manually operable cam 19, the other end thereof being 90 connected to the lever 15 by some flexible connection 20.

It will be obvious from the foregoing description that the inclination or adjustment of an end section 4 may be accomplished by 105 manipulation of the connection with the lever 15 in such manner as to cause the latter to withdraw the bolt from the segment plate 6. Release of the manipulative connection will permit the bolt to automatically reen- 110

gage with its locking plate in the usual manner.

Having thus described my invention, what I claim as new is:—

5 In a bedstead of the class described, a main frame, locking segments attached to said main frame at either side, an adjustable section of substantially U-shape pivotally connected to the main frame, the end portions 10 thereof being bent downwardly adjacent to the pivot to form supporting arms, locking means mounted on each of said arms com-

prising a U-shaped keeper secured to the inner face, a spring actuated locking bolt mounted in the keeper and projecting 15 through the arm, said keeper having a supporting extension projecting therefrom, a lever pivoted to said extension for retracting the bolt, and a flexible actuating connection extending from said lever to the end of 20 the adjustable section for unlocking the bolt to permit of adjustment of said section.

In testimony whereof I affix my signature.

WILLIAM J. CURTIS.
